(57) **CLAIM**

The ornamental design for a yogurt maker, as shown and described.

DESCRIPTION

FIG. 1 is a perspective view of a yogurt maker showing my new design;

FIG. 2 is a front elevational view thereof, the rear elevational view being a minor image.

FIG. 3 is a left side elevational view thereof, the right side elevational view being a mirror image.

FIG. 4 is a top view thereof;

FIG. 5 is a bottom view thereof;

FIG. 6 is an exploded view thereof; and,

FIG. 7 is a cross-sectional view thereof taken along lines A-A of FIG. 4.

Broken lines are included herein for illustrative purposes only and form no part of the claimed design.
